FIG.1

FIG.2

FIG.3

FIG.5

FIG.4

FIG.6

FIG. 1 is a perspective view showing my new auto drip pan, the securing washer being omitted for convenience of illustration;

FIG. 2 is a top plan view thereof;

FIG. 3 is a bottom view thereof;

FIG. 4 is a side elevational view thereof with the securing wires being broken away for convenience of illustration, with the side opposite that shown in FIG. 4 being identical to the side shown in FIG. 4.

FIG. 5 is a front elevational view of said auto drip pan; and

FIG. 6 is a rear elevational view thereof with the securing wires being broken away for convenience of illustration.

It is understood that the mesh material on the bottom surface as shown in FIGS. 1 and 2 covers the entire area indicated.

I claim:

The ornamental design for an auto drip pan, as shown and described.
